UNITED STATES PATENT OFFICE.

JOHN POWELL, OF KIDDERMINSTER, ENGLAND, ASSIGNOR TO HENRY JECKS
DIXON & SONS, OF SAME PLACE.

DESIGN FOR CARPET.

Specification forming part of Design No. 6,337, dated January 7, 1873.

To all whom it may concern:

Be it known that I, JOHN POWELL, of Kidderminster, in the county of Worcester, in England, have invented a new and original Design for Carpets; and I do hereby declare that the following is a full, clear, and exact description thereof, which will enable others skilled in the art to make and use the same, reference being had to the accompanying photographic illustration forming part of the specification.

This design consists of a large shield resembling a parallelogram with a semi-oval projection on each of its ends and sides. Around the figure runs a deep border of dark colors, with an inner border of a lighter shade and narrower width. The middle of the shield is of a light color, on which rests a large bouquet of flowers and leaves having a peony or rose in full bloom in the center.

This shield is linked to a similar one at each end, the connection with one being a simple bar of a dark color, and with the other a small shield similar in pattern to the large ones, and placed transversely. This shield is ornamented with fleur-de-lis placed at each point of a diamond so as to form a cross, which is surrounded by a light beaded line which runs parallel with the outlines of the shield, leaving it a broad border, in deep colors. The ground of the carpet is light, and over it is trailed a flowering vine.

I claim as my invention—
The design for carpets, as shown.
JOHN POWELL.
